UNITED STATES PATENT OFFICE.

THOMAS A. MORRIS, OF NEW YORK, N. Y.

RADIATOR SHUTTER.

1,411,866.

Specification of Letters Patent. Patented Apr. 4, 1922.

Application filed December 13, 1919. Serial No. 344,527.

To all whom it may concern:

Be it known that I, THOMAS A. MORRIS, a citizen of the United States of America, residing at city, county, and State of New York, have invented new and useful Improvements in Radiator Shutters, of which the following is a specification.

This invention relates to air-deflecting shutters or vanes for regulating the cooling effect of radiators especially for the circulating water or other liquid used in the water-jackets of motor-cars, tractors, airplanes or other apparatus employing internal combustion engines.

15 The principal object of the invention is to provide a novel means for regulating the flow of air through the radiator.

Another object is to increase the cooling effect of the radiator by the attachment to 20 it of a metal structure having a great amount of radiating surface.

A further object is to deflect the course of the cooling air from a substantially horizontal plane (or a plane parallel to that 25 in which the car or other vehicle is travelling) to a plane at a considerable angle thereto, in order to increase the radiating efficiency of the structure.

Another object is to provide means for 30 converting the usual form of radiator (without regulating device) into a more efficient structure which may be controlled by the operator to adapt it for varying weather conditions. The invention is not limited to an attachment for radiators as 35 it may be incorporated in the radiator structure.

Other and ancillary objects will appear hereinafter.

40 In the accompany drawings which illustrate the invention,

Fig. 1 is a perspective view of the forward portion of a motor car showing the shutter-structure attached to the radiator 45 and the controlling device extending back to a point within reach of the driver.

Fig. 2 is a vertical section through the shutter-structure in its closed position, showing the radiator in outline partly broken 50 away;

Fig. 3 is a similar view of the shutter-structure in its open position;

Fig. 4 is a perspective view of a fragment of one of the sheet-metal shutter-members; and

Fig. 5 is a horizontal section taken on the line 5—5 of Fig. 3, partly broken away.

Referring to the drawings, the air deflecting and regulating means consists of two similar members 1 and 2, each consisting of a single piece of sheet metal. The member 1 is sheared, slitted or otherwise cut to form vertical strips 3 and 3' and horizontal vanes 4, which are bent at an angle of approximately 45° from the vertical plane of the sheet from which they are cut. Although the structure illustrated is formed of sheet metal, it is obvious that the device may be made of cast metal parts.

To the vertical strips 3' are attached by 70 soldering or other means, vertical webs 5 for strengthening the structure. The ends of the vanes 4 are also soldered or otherwise attached to the sides of the webs 5, so that

each vane is attached at one end to a vertical 75 strip 3, at the other end to the vertical strip 3' and it is also attached to a vertical web 5.

The member 2 is similarly formed of vertical strips 6 and 6', horizontal vanes 7 and webs 8. The vertical strips 3' and 6' 80 are of a width approximately the same as the thickness of the webs 5 and 8 so that the ends of the vanes 4 and 7 which are attached to the strips 3' and 6' are in contact

with the webs 5 and 8, and may be attached 85 readily thereto by solder or other means. The vertical strips 3 and 6 and the spaces between the unattached ends of the vanes 4 and 7 are slightly greater in width than the thickness of the webs 5 and 8 to provide 90 clearance between the unattached ends of the vanes 4 and 7 and the webs 5 and 8,

and permit the movement of member 1 in relation to member 2 without friction between the unattached ends of the vanes 4 95 and 7 and the adjacent sides of the vertical webs 5 and 8, with which they are interlocked, but not in contact due to the clearances described.

Fig. 2 shows the member 1 in the position 100 which entirely shuts off the air from the radiator 9, the member 1 being interlocked with the member 2 so that the rear edges of the vanes 4 are in contact with the front surfaces of the vanes 7 and the front edges 105 of the vanes 7 are in contact with the rear surfaces of the vanes 4.

Fig. 3 shows the member 1 moved away from the member 2 to permit the free passage of air between the several vanes 4 and 110

the several vanes 7, which now register with them to form a series of angular passages or ports, open at both ends.

The movement of member 1 is accomplished by means of an arm 10, pivoted at 11 and actuated by a rod 12 which passes through the radiator and under the hood of the motor car to the control-board, where a handle 13 is provided, by means of which 10 the rod 12 may be pushed forward to open the shutters or pulled back to close them. The flat bar 14 extends entirely across the top of the shutter structure and engages at its edges in slots 16 in the webs 5 of the 15 member 1 and in slots 18 in the webs 8 of the member 2. Where desired the edges of the bar 14 may be provided with round portions as at 15 to improve the bearing surfaces where the bar engages with the 20 webs of the members 1 and 2.

Parallel movement of the member 1 in relation to the member 2, is accomplished by means of the bars 19 and 20, which pass through round holes 21 and 22 in the webs 25 8 and through slots 23 and 24 in the webs 5. The slots 23 and 24 are placed at the same angle as the vanes 4, so that movement of the member 1 is in a plane parallel to the plane in which the vanes 4 are set, and 30 transverse to the plane in which the vanes 7 are set. The front edges of the vanes 7 are always adjacent to the rear surfaces of the vanes 4; this relation of parts resulting in a series of angular air-passages or ports 35 which may be adjusted to any size from zero to maximum by the movement of member 1 in relation to member 2, as above described.

The member 2 is held in intimate contact with the radiator 9, by means of bolts 40 25 which engage with the webs 8. Heat from the radiator is carried by conduction to the members 1 and 2, which present large radiating surfaces to the air which passes 45 through them. The efficiency of the radiator is therefore increased to a marked degree by the attachment of the shutter structure.

The angular relation of the vanes 4 and 7 50 causes the cooling air to change direction as it passes through the passages formed by the vanes and to impinge upon the radiating surfaces with a pressure which increases as the square of the speed. The 55 radiating effect of the shutter-structure therefore increases in the same proportion as the load on the engine due to the resistance of the air. It is therefore unnecessary to shift the adjustment as frequently as 60 would be desirable if the shutters were set in a plane parallel to the plane of motion of the car, or were set at various angles to effect the adjustment.

What I claim is:

65 1. In air-regulating means for radiators,

the combination with a member provided with a series of vanes, of another member also provided with a series of vanes, the two sets of vanes being in angular relation to each other.

2. In air-regulating means for radiators, the combination with a member provided with a series of vanes, of another member provided with a series of vanes in angular relation to the first series of vanes and 75 means for varying the relation between the two series of vanes.

3. In air-regulating means for radiators, the combination with a member provided with a series of vanes immovably fixed 80 thereto, of another member provided with a series of vanes in angular relation to the first series of vanes, and means for varying the relation between the two series of vanes.

4. In air-regulating means for radiators, the combination with a member provided with a series of parallel vanes, of another member provided with a series of parallel vanes, the vanes of one member being at 90 an angle to those of the other member and means for moving one member relatively to the other member.

5. In air-regulating means for radiators, the combination with a member provided 95 with a series of parallel vanes, of another member provided with a series of parallel vanes, the vanes of one member being at an angle to those of the other member and means for moving one member in a plane 100 parallel to the plane of the other member.

6. In air-regulating means for radiators, the combination with a member provided with a series of parallel vanes, of another member provided with a series of parallel 105 vanes, the two series of vanes being transverse to each other, and means for moving one member in a plane parallel to the vanes on that member.

7. In air-regulating means for radiators, 110 the combination with a member provided with a series of parallel vanes of another member provided with a series of parallel vanes, the vanes of one member being at an angle to those of the other member, 115 both members being provided alternately with parallel webs transverse to the vanes, and spaces between the ends of adjacent vanes for receiving the webs of the other member, the two members forming a complete screen when they are in contact with 120 each other.

8. In air-regulating means for radiators, the combination with a member provided with a series of parallel vanes, of another member provided with a series of parallel vanes, the vanes of one member being at an angle with those of the other member, both 125 members being provided alternately with parallel webs transverse to the vanes, and 130

spaces between the ends of adjacent vanes for receiving the webs of the other member, bars for connecting the two members, passing through holes in the webs of one member and through elongated slots in the webs of the other member, and means for effecting the movement of one member relatively to the other member, consisting of a bar engaging at one edge with slots in the webs

of one member and engaging at the other 10 edge with slots in the webs of the other member and a crank arm attached to the bar.

In testimony whereof I have signed this specification this 25th day of November, 15 1919.

THOMAS A. MORRIS.
